(57) **CLAIM**

The ornamental design for a charging box for electronic cigarette as shown and described.

DESCRIPTION

1.1 : Perspective

1.2 : Perspective

1.3 : Front

1.4 : Back

1.5 : Left

1.6 : Right

1.7 : Top

1.8 : Bottom

2.1 : Perspective

2.2 : Perspective

2.3 : Front

2.4 : Back

2.5 : Left

(Continued)

2.6 : Right

2.7 : Top

2.8 : Bottom

The dashed broken lines and faded portions within dot-dash broken lines depict portions of the charging box for electronic cigarette which form no part of the claimed design.

1 Claim, 16 Drawing Sheets
